SWIVEL ELECTRICAL CONNECTION

Albert E. Caldwell, Galesburg, Ill., assignor to
 Eby Inventions, Inc., Philadelphia, Pa., a corporation of Pennsylvania

Application July 9, 1934, Serial No. 734,308

10 Claims. (Cl. 173—324)

This invention relates to swivel electrical connectors and more particularly is directed to such connectors as employed to effect detachable electrical connection between an outlet and an electrically operated appliance, such as the connections between a flexible conductor and a wall socket or outlet, or a flexible conductor and the appliance which is supplied with current thereby.

In my copending application, Serial No. 621,079, filed July 6, 1932, which has matured into Patent No. 2,055,999 on Sept. 29, 1936, I have disclosed one form of a swivel connector of this type, commonly called a push plug or prong plug having extending contact prongs adapted to be engaged within a receptacle such as a wall socket or the like, and which in turn is provided with contact members adapted to be engaged by a second contact plug carried by the flexible conductor, the contact members being rotatably carried by the cover of the push or prong plug to provide a swivel connection between the plug connected to the cord and the prong plug.

The present invention has for its primary object the provision of a swivel connector of a basic design that may be incorporated in a plurality of different types of swivel connectors, and which provides a free swiveling connection having relatively small frictional resistance to rotation so that connection thereto and subsequent rotation of the connector means may be facilitated.

In the development of modern portable electrical appliances, it has become customary to provide a flexible connector or conduit extending from the appliance to an adjacent electrical outlet. However, in the use of such appliances as trouble lamps, electric irons, vacuum cleaners, ordinary portable lamps and the like, these flexible conductors have a tendency to become kinked or twisted, and to remedy this undesirable situation I have provided a swivel electrical connector which is capable of automatically rotating to accommodate any twisting or kinking tendencies of the cord. Further, wall outlets are sometimes so situated as to be inconvenient of access, or disposed in a relatively dark location where the position of the openings for receiving the contact prongs cannot be readily ascertained. By the provision of a swivel connector of the type disclosed in the present invention, the insertion of the contact prongs connected to the electrical cord is facilitated by a cooperating rotation of the cover of the connector, whereby the openings are brought into register with the contact prongs by application of axial pressure to the prongs, and the cord can thus be readily con-

nected without turning it into a predetermined position to align it with the contact prong-receiving openings of the receptacle.

Another object of the present invention is to provide a swivel connector having bearing surfaces about which the rotation occurs, which surfaces are also employed for carrying the electrical circuit through the device. By this construction I provide a wiping contact surface which is always maintained clean and bright by the rotation effected during connection and operation of the device, and which therefore reduces the electrical resistance through the device.

A distinct advantage secured by the present invention is the adaptability of the basic construction for use in a plurality of different types of connector devices, including the connectors between the current conductors or cord and the appliance, so that, if desired, swivel connections may be provided at each end of a flexible conductor or cord. Also, threaded plug connectors for use in connection with threaded outlet sockets may be provided with the swiveling means of the present invention.

In addition, the present invention is capable of providing a unitary wall outlet construction having the swiveling means of the present invention incorporated therein, whereby no additional swiveling connectors need be provided for attachment of a flexible cord thereto.

A further feature of the present invention is the provision of resilient means for spacing the cover of the connector device a slight distance away from the defining edge of the receptacle, to decrease the frictional resistance to rotation, the resilient means being independent of the electrical circuit extending through the device.

A still further object of the present invention is the provision of a compact and simplified construction in which all of the current conducting parts may be economically formed and assembled, the contact-engaging and conducting members being preferably formed from metal stampings. Another advantage secured by reason of this construction resides in the feature of having all of the rotatable elements carried by the swiveling member, and mounted upon a single centrally extending post which forms a part of the electrical circuit, whereby the swiveling contact members may be readily assembled in position upon the post, together with the cover, and this structure may then be secured to the receptacle in order to form the complete contact connector.

Other objects and advantages of the present

invention will appear more fully from the following detailed description, which, taken in connection with the accompanying drawings, will disclose to those skilled in the art the construction and operation of a preferred form of the present invention.

In the drawings:

60 Figure 20 is a sectional view taken substantially on the line 20—20 of Figure 18, looking in the direction indicated by the arrows; and

Figure 21 is a plan view of the insulating member shown in Figure 19.

65 Referring now in detail to the drawings, the plug shown in Figures 1 to 4, inclusive, comprises a receptacle or casing 5, formed of insulating material, such as a molded phenol condensation product or the like, and which is provided with a pair of projecting contact prongs 6 and 7, extending in spaced relation from the lower end thereof, the prongs 6 and 7 being adapted to enter through suitable openings in a

70 wall socket or the like to effect electrical contact 75 with the contacts disposed within such an out-

let. Mounted for rotation within the receptacle 5 is a swivel cover 8, which also is formed of suitable insulating material, such as molded or pressed phenol condensation material or the like.

5 The cover 8 is provided at its center with a boss portion shown at 9, having a recess 10 of hexagonal or other suitable polygonal shape formed therein. Disposed upon opposite sides of the boss 9 are a pair of openings 12, which are adapted to receive the contact prongs of a plug connector carried by a flexible cord or the like. The openings 12 are located a considerable distance below the upper surface of the cover 8, and are separated by a defining ridge 13 which extends from the outer periphery of the cover 8 inwardly to the central boss 9. This ridge is provided with opposed sloping surfaces 14, which extend downwardly toward the openings 12.

20 The peripheral surface of the cover 8 is provided with a rounded or concaved depressed portion 15 which forms a camming surface for guiding the prong plugs or the like into the openings 12, cooperating with the surfaces 14 formed by the ridge 13. This provides a substantially 25 dished or concaved surface leading to each of the openings 12, so that regardless of the angular position of the cover 8 with respect to a pair of prong members which are to be inserted therein, the camming surfaces will effect rotation of the cover 8 to align the openings 12 in position with respect to the prong members which are to be inserted therethrough.

25 The cover 8 is rotatable about a centrally extending post or stud member 16, which at its 30 upper end is provided with a frusto-conical bearing surface 17 adapted to engage over a corresponding surface formed in a retaining nut 18 having its outer peripheral surface formed to correspond to the periphery of the opening 10, 40 in the present embodiment being hexagonal in shape. Thus, the nut member 18 rotates with the cover 8, and has bearing engagement about the outwardly flared surface 17 of the post 16.

45 At its lower end, the post 16 is provided with a portion of reduced diameter, indicated at 19, which projects through an opening formed in the base of the receptacle 5, the receptacle 5 being provided with a raised boss portion 20 through which the portion 19 of the stud 16 extends.

50 A suitable recess is formed in the outer surface of the base of the receptacle 5, and is adapted to receive the normally extending portion 22 of the prong 6, which lies within this recess, to prevent rotation of the prong with respect to the receptacle, and the outer projecting end of the stud 16 is beaded or spun over, as shown at 23, for rigidly securing the post in position within the receptacle 5, and at the same time clamping the prong 6 in nonrotative and fixed 60 position with respect to the receptacle.

65 The cover 8, adjacent the opening 10, is provided with a depending central portion indicated at 24, which is suitably recessed, as indicated at 25, to provide an annular chamber about the stud 16 in which is disposed a spring member 26, which bears at its upper end against the lower surface of the nut member 18, and at its lower end is biased against a sleeve member 27 extending upwardly about the stud 16, and having an 70 upwardly flared portion cooperating with a corresponding reduced portion of the recess 25 for securing it in position with respect to the depending portion 24 of the cover 8.

75 The lower end of the sleeve 27 is spaced a slight

distance above the boss 20 formed in the receptacle 5, as shown at 28 in Figure 4, and, by reason of the resiliency of the spring member 26, allows a slight relative movement of the cover member 8 axially with respect to the stud 16, the amount of this movement being limited by the space between the lower end 28 of the sleeve 27 and the upper end of the boss 20. This provides for spacing the cover 8 a slight distance 10 away from the peripheral edge 29 of the receptacle 5, whereby its frictional resistance to rotation is materially decreased.

Considering now in detail Figure 3, a pair of contact fingers, formed from resilient metal stampings, are indicated at 30 and 32, respectively, the contact finger 30 being shown in detail in Figure 5. This contact finger is provided with a doubled back portion indicated at 30a, which is adapted to have wiping contact engagement with a prong member inserted through the opening 12. The main portion of the contact finger 30 extends downwardly along the outer surface of the depending portion 24 of the cover 8, being spaced away therefrom by a laterally bent portion 33, and having a supporting flange or tab 34 extending normal thereto and engaging about the lower end 28 of the sleeve member 27, the flange 34 being apertured to have relatively tight fit over the outer surface of the sleeve member 27 and bearing against the projecting portion 28 thereof. It is therefore apparent that an electrical circuit can be traced from the contact prong which enters the opening 12 and engages the portion 30a of the contact finger 30, through the contact finger 30 and the sleeve 27 to the post or stud 16, and then downwardly through the post or stud to the portion 22 of the contact prong 6.

The opposite contact finger 32 is formed in substantially the same manner, but is insulated from the post 16 by reason of the depending portion 24 of the cover 8, and the insulating member 31, the contact finger 32 having a relatively large opening extending about portion 24 of the cover. Disposed immediately above the inner extending flange portion 35 of the contact 32 is a contact clip indicated in detail in Figure 7.

This contact clip has bearing engagement on its lower surface with the upper surface of the flange portion 35 of the contact finger 32, the clip 36 having an aperture 37 formed therein which engages about the lower end of the depending portion 24 of the cover. Formed integrally with the clip 36, and extending laterally and upwardly therefrom are a pair of tongue members 38, which are provided with rounded and downturned end portions 39, as shown in detail in Figure 7. The under surfaces of the laterally and downwardly turned ends 39 are adapted to receive the upper projecting ends 40 of a second contact clip member 41, shown in detail in Figure 6. The contact clip member 41 is adapted to extend downwardly, having an outwardly flared central portion provided with a raised frusto-conical surface 42. This frusto-conical surface 42 is adapted to extend over a corresponding frusto-conical surface 43 formed upon a laterally extending portion 44 of the prong 7. This frusto-conical portion 43 of the prong 7 engages about and is secured in contact with the extending boss 20 of the receptacle 5, and the inner surface of the raised portion 42 of the contact clip 41 has rotative bearing engagement thereabout, thereby extending a circuit 70 from the contact finger 32, flange portion 35

thereof, first contact clip 36 and its extending arms 38 to the arms 40 of the contact clip 41, and thence downwardly through the frusto-conical bearing surfaces 42 and 43 to the terminal prong 7.

The spring 26 presses against the sleeve 27, and the lower end of the sleeve 27 is spaced away from the boss 20 by reason of the contact clip 41 bearing upon the surface 43. Thus, the spring pressure serves to press the surface 42 against the surface 43 to maintain a positive wiping contact therebetween to insure good electrical conduction across these surfaces. The friction of rotation of the cover 8 with respect to the receptacle 5 is taken up between the contact surfaces 42 and 43, and about the outwardly flared surface 17 which engages the nut member 18. Since the surfaces are smooth, there is relatively little frictional resistance to rotation, inasmuch as the area of the surfaces is maintained small with respect to the peripheral extent thereof, and consequently the cover 8 rotates freely about the stem 16, and, with the grooves formed in the corner, is capable of readily rotating and positioning itself to accommodate contact prongs extending into the openings 12. The contact fingers 30 and 32, which rotate jointly with the cover, will thus always be disposed in alignment with the opening 12, whereby they may be readily engaged by the contacts extending therethrough.

Referring now to Figures 8 to 10, inclusive, the same swiveling construction as provided by the embodiment shown in Figures 1 to 7, inclusive, is disposed herein, but is shown as applied to a threaded plug instead of a contact prong or push plug. The cover member 45 shown in Figures 8 and 10 corresponds in design to the cover member 8 of the previous embodiment. This cover member is provided with corresponding openings, for the reception of prong contacts, and has corresponding contact fingers 30 and 32 disposed therein and rotatable therewith for extending the electrical circuit from the contact fingers of a push type or end connection plug of an electric cord to the connector. The receptacle 46, shown in section in Figure 10, is substantially cup-shaped in form, and is provided with an outwardly extending shoulder portion extending under and aligned with the cover 45. About the cylindrical portion of the receptacle 46 is disposed a metallic shell member 47 having threads formed thereon adapted to be engaged in suitable threads formed in a wall socket or the like. This is of standard construction, and needs no specific description.

Adjacent the lower end of the receptacle 46, and extending thereacross is an insulating washer 48, which is centered about the extending portion 49 of the stem 16'. A flanged cup-shaped member 50 formed of metal, is disposed in inverted position on the insulating washer 48, and solder or the like is poured therein, and secures the head 51 of the extending portion 49 of the stud 16' to the metal cup 50, forming one terminal of the plug. The other terminal comprises the laterally extending portion 44' of a terminal contact similar to the prong 7 of the embodiment shown in Figure 1, which is bent upwardly at 52 within a suitable cut-out portion of the receptacle 46, and is soldered or sweated to the inner periphery of the metallic threaded cylinder 47 to extend the electrical circuit from contact 32 to the threaded member 41 providing the other terminal of the plug. The washer 48 is secured against rotation by interlocking engagement with two ex-

tending tongue portions 53 formed at the lower end of the receptacle 46. The operation of the structure is the same as described in connection with the previous embodiment, the only variation from the structure shown in Figures 1 to 7, inclusive, being the formation of the terminal portions of the member, since the prongs 6 and 7 are replaced by the terminals 51 and 41.

Referring now to the embodiment shown in Figures 11 and 12, this shows a duplex type of wall socket or receptacle provided with swiveling connections of the type previously described. A pair of rotatable cover members 55, corresponding in design and construction to the covers 8 and 45 of the previous embodiment, are provided, and are mounted upon a pair of extending stud members 56 and 57 secured in a single housing 58 which extends behind the wall plate or facing plate 58'. The extending ends of the studs 56 and 57 are joined by a substantially T-shaped connecting member 60, which member has a down-turned portion 61 provided with a screw or terminal lug 62 for securing a conductor thereto. This construction is shown in detail in Figure 12. The other terminal, indicated at 63, corresponds to the terminals 44 and 44' of Figures 3 and 10, but is extended between the two studs 56 and 57, the housing 58 being provided with cutout portions indicated at 64, which accommodate the insertion of the terminals 63 thereinto. The two terminals 63 of the duplex socket are joined by an integral tongue 65, which is provided with a terminal nut 66 for connecting an electrical conductor thereto.

The internal construction of each of the outlet sockets formed in the receptacle shown in this embodiment is the same, and is identical with the construction shown in the embodiments of Figures 1 and 8. Thus, two contact fingers 30 and 32 are provided, and are aligned for rotation with the openings 12 formed in the cover members 55 for engaging contact prongs inserted through these openings. Also, the bearing engagement between the contact clip 41 and the raised bearing surface 43 is the same as previously described, and extends the circuit from the contact finger 32 to the terminal 65. In the same manner, the circuit from the contact finger 30 is extended through the sleeve 27 to the stud members 56 and 57, and thence through the terminal member 60 to the terminal lug 62.

It will be noted that in each of the three embodiments described, the construction of the swivel connector structure and cover is identical, being embodied in three different types of receptacles. It is thus apparent that the swiveling connection means of the present invention may be equally well applied to a separate contact plug of the push type or of the threaded socket type, or may be formed within a wall outlet or receptacle of either single or duplex construction.

In Figures 13 to 17, inclusive, I have shown a swivel connector of the present invention as applied to the connection between an electric cord and an electric iron or similar electrically operated appliance. The ordinary type of insulated handle or similar disconnect means is shown at 67, having oppositely disposed finger portions 68 and 69. Depending from a recessed portion thereof is a relatively strong helically coiled spring member 70, within which extends the two conductors 71 and 72 which extend the circuit to the electrically operated mechanism within the appliance, there ordinarily being a terminal socket carried by the resilient spring means 70 and

which extends over a pair of contact plug terminals secured to the appliance.

A flexible electrical cord is indicated at 73, and has the conductors 74 and 75 disposed therein in insulated relationship. This cord 73 is adapted to enter into a cup-shaped socket 76 through a resilient supporting means, comprising a spring member 77 provided with an upper flanged cap member 78 forming a smooth guideway for the cord 73, to prevent abrasion of the insulation 10 thereof.

The insulated handle 67 is provided with a recess 79, and the base portion of the recess 79 is provided with a raised boss portion 80 corresponding to the boss portion 20 of the embodiment shown in Figures 1 to 12, inclusive. A stud member 82, corresponding to the stud member 16, is supported in this raised boss portion, and at its lower end is connected to a terminal member 83 having an outwardly extending portion 84 to which the conductor 71 is soldered or otherwise suitably mechanically and electrically connected. The stud member 82 at its upper end has an outwardly flared head portion 85, which is engaged by a locking nut member 86 in the same manner as described in connection with the previous embodiment. A rotatable insulating member 87, corresponding to the cover members 8, 45 and 55 of the previously described embodiment, is provided with openings 88 through 30 which the bared ends of the conductors 74 and 75 extend. A spring member 89 is provided for biasing the nut member 86 upwardly against the flanged end of the stud 82, and for pressing downwardly upon a sleeve 90 corresponding to 35 the sleeve 27 of the previous embodiment.

A pair of resilient contact fingers 92 and 93 are provided, the contact finger 92 being shown in detail in Figure 16, and comprising a base portion extending substantially normal to the stud member 22 and having an enlarged opening 94 therein which is adapted to extend about the sleeve member 90 and to bear against the flange 95 formed at the lower end of the sleeve member. At its upper end, the contact finger member 92 is provided with a notch or similar cutout portion 96, which is adapted to extend over and receive the bared end of the conductor. It is to be understood that any suitable conductor engaging means may be provided at the free end 50 of the contact finger.

The contact finger 92 therefore extends an electrical connection from the conductor 75 through the contact finger, through the sleeve 90, and the stud 82 to the terminal 83, and thence to the conductor 71. The contact finger 93 is similar to the contact finger 92, but is provided with an enlarged opening of greater diameter than the opening 94 of the contact finger 92. This contact finger is mounted about an extending portion of the member 87, which is formed of insulating material, and is spaced from the contact finger 92 by an insulating member indicated at 97. The insulating member 97 corresponds generally to the insulating member 31 interposed between the contact fingers 30 and 32 in the embodiment shown in Figures 1 to 12, inclusive.

The upper surface of the inwardly extending portion of the contact finger 93 is engaged by a contact member indicated generally at 98 in Figure 17, this member having an opening 99 therein fitting over the lower extending end of the member 87, and having a pair of upwardly extending contact fingers 100, which are adapted 75

to be engaged by corresponding upwardly extending arms 102 formed integral with and carried by a contact member 103 corresponding to the contact member 41 of Figure 6, the arms 102 corresponding to the arms 40 shown in this figure. These arms have relative sliding engagement therebetween, the lower end of the member 103 being provided with a raised frusto-conical contact surface 104 adapted to have bearing engagement about a corresponding surface 105 formed on a terminal member 106 which extends downwardly through the opening 107 formed below the recess 79 of the member 67, and which is adapted to be engaged mechanically and electrically by the bared end of the conductor 72.

The contact finger 93 therefore extends an electrical circuit from the conductor 74 through the finger 93, and thence through the contact clip 98 and its extending arms 100 to the extending arms 102 of the member 103, and thence through the corresponding contact surfaces 104 and 105 to the terminal 106 and conductor 72.

The principal features of the construction shown in Figure 14 correspond to the construction shown in Figures 3 and 10, the cup-shaped member 76 being slid downwardly over the member 87 and engaging bowed portions of the contact fingers 92 and 93 to force these fingers into tight contacting engagement with the bared ends 75 of the conductors 74 and 76. The cord 73, the receptacle 76, the member 87, and the contact fingers and the member 103 are all rotatable about the stud 82, so that any tendency of the cord 73 to twist or kink, is eliminated by this swiveling connection. To disconnect the lamp cord, all that is necessary is to slide the member 76 upwardly, which releases the pressure against the contact fingers 92 and 93, and allows the bared ends 75 and 74 of the conductors to be released from the member 87. Ordinarily however, the cord is maintained in connected position, the connection to and disconnection from the appliance being accomplished by the terminal socket disposed below the spring 70, or by a disconnect plug carried at the opposite end of the cord 73, which is engaged within a current-connecting receptacle similar to that shown in any of the embodiments described in connection with Figures 1 to 12.

In Figures 18 to 21, inclusive, I have disclosed a swivel connection of the construction described previously, adapted for use in a trouble lamp socket or the like.

In this embodiment, a trouble lamp or light bulb is indicated at 110 and is adapted to be secured within a socket 112 carried within a substantially cylindrical holder 113 having an annular flange 114 at its upper end. Mounted below the flange 114 about the surface of the holder 113 is a clamp member 115, which is provided with a plurality of guard members 116 forming a cage enclosing the bulb 110 and protecting the same from mechanical injury.

The holder 113, below the socket 112, is provided with a portion 117 of reduced diameter, which at its lower end is provided with an annular peripheral bead 118 having a corresponding annular groove 119 formed on the inner surface thereof. A cup-shaped receptacle 120 is adapted to be inserted into the lower end of the holder 113, and is preferably formed of insulating material or the like. This corresponds to receptacle 5 of Figure 1. The member 120 is provided with a raised boss portion 122, through which a stud member 123 extends, the stud member 123 being

provided with an outwardly flared head portion 124 having bearing engagement with a nut member 125. At its opposite end, the stud member 123 extends through the boss 122 of the receptacle 120, and its head portion is secured over 5 and mechanically and electrically connected to a terminal lug 126, which carries an eyelet 127 at its free end, the eyelet 127 being adapted to receive a conductor 128 which is soldered or otherwise secured thereto. The conductor 128 10 extends upwardly and is connected to the terminal 129 of the socket member 112.

Extending through the base portion of the receptacle 120 is a second eyelet 130, which is adapted to receive the conductor 132, the conductor being soldered or otherwise suitably secured therein, and extending upwardly and being connected to the terminal 133 of the socket 112. The socket 112 is thereby electrically connected to the stud 123 and to the eyelet 130 20 carried by the receptacle 120.

Mounted over the boss portion 122, and rigidly secured in position by the eyelet 130 is a terminal member 134, corresponding to the members 104, 40 and 44 of previous embodiments, and which forms an opposite terminal connection for the conductor 132. The trouble lamp cord 135, which is connected to a suitable source of electrical current supply, has the two conductors 136 and 137 thereof connected respectively to the terminals 138 and 139 formed within the cup-shaped terminal socket 140 which surrounds the conductor 135.

A cover member 142, provided with a cylindrical extending portion, is mounted for rotation 35 about the stud 123, and the cylindrically extending portion thereof extends into the receptacle 120. A pair of contact terminals, indicated at 143 and 144, are connected through stud members 145 and 146 to terminal members 147 and 148, which extend the electrical connections from the terminals 143 and 144 to the terminals 134 and the stud member 123, respectively, through the same type of contacting engagement as described in connection with Figures 13 to 17, 45 inclusive. The terminal portions 143 and 144 of the cover member 142 extend outwardly from the cover 142, and are provided with annularly grooved portions 149, which are adapted to be engaged with suitable camming terminals or plates 150 and 151 connected to the terminal lugs 138 and 139. These camming terminal plates 150 and 151 are so formed that the terminal portions 143 and 144 may first be positioned and extend therethrough as shown in 55 dotted lines in Figure 20. Upon rotation of the member 140, which is provided with a shoulder upon which the terminal cam plates 150 and 151 are supported, the terminals 143 and 144 are locked, by means of the annular grooves 149 60 formed therein, in the position shown in full lines in Figure 20, whereby the member 140, together with the conductor 135, is mechanically and electrically connected to the cover 142, and is mounted for conjoint rotation therewith. 65 Since the cover 142 is rotatable about the stem 123, it is apparent that a swiveling connection is provided, so that the cord 135 will have no tendency to become kinked or twisted. A suitable 70 insulating member 155, shown in Figure 21, is provided with opposed cut-out portions 156 through which the terminals 143 and 144 are adapted to extend down into engagement with the camming plates 150 and 151, whereby the 75

member 140, and terminal lugs 138 and 139, are insulated with respect to the cover 142.

- In the assembly of the construction shown in this embodiment, the socket 112 is first mounted 5 in the position shown, with the conductors 132 and 128 connected thereto and being of sufficient length to extend outwardly of the lower end 118 of the holder. The receptacle member 120 is then connected, by means of the eyelets 130 and 10 127, to the conductors 128 and 132, and is then moved inwardly into locking engagement with the peripheral bead 119 of the holder, the conductors 128 and 132 being at the same time forced into the space 157 in the holder.
- 15 After the receptacle 120 has been placed in position, the cover 142 being mounted thereon for rotation as previously described, the conductor 135, which has its conductors 136 and 137 connected to the camming plates 150 and 20 151, is locked in position with respect to the terminals 143 and 144 by being inserted over the terminals and then rotated to lock the terminals in the position shown, as previously described. This completes the electrical connection to the 25 light member 110.

It is apparent that the present invention provides a basic construction for a swiveling connection which may be employed in connection with a multiplicity of different types of swivel 30 electrical connections, and which may be disposed either at the wall outlet or receptacle, being formed as a part of the wall outlet, or as a separate and individual prong or push type of plug or socket type of plug, or may be provided 35 for effecting connection between an electric supply cord and an electrically operated appliance, such as a trouble lamp or electric iron or the like.

The principles embodied in the present invention, as shown, are applicable to a wide variety 40 of uses, of which only a few have been shown and described herein. I therefore do not intend to limit myself to the exact applications of the invention which have been shown and described 45 in detail herein, but only as defined by the scope and spirit of the appended claims.

I claim:

1. Swiveling connector means for extending electrical circuits from a pair of spaced contact 50 members carried by a rotatable insulating member to a pair of fixed terminals, comprising a central post connected to one of said terminals and having bearing means for supporting said insulating member for rotation thereabout, a 55 contact sleeve carried by said insulating member and having contacting engagement with said post, means for supporting one of said contact members on said sleeve, a second contact member having rotative contacting engagement with 60 the other of said fixed terminals, said second contact member having opposed diverging contact arms, and an intermediate contact member extending between the other of said spaced contact members and having corresponding arms 65 resiliently engaging said contact arms, whereby said second contact member is locked for joint rotation with said other of said spaced contact members.

2. Means providing a swiveling connection between an electric cord and an electrical current supply outlet comprising a cup-shaped receptacle having terminal members extending to the outer surface of said receptacle, a post extending axially in said receptacle and having engagement 70 with one of said terminal members, an insulat-

ing cover member having bearing means engaging the extending end of said post providing for rotation of said cover thereabout, said cover having opposed openings for receiving contact members carried by said cord, contact fingers 5 carried by said cover within said receptacle adapted to be engaged by said contact members, means for connecting one of said fingers to said post, means resiliently spacing said cover out of engagement with said receptacle and providing an electrical connection between the other of said contact fingers and the other of said terminal members, and spring means tending to urge said cover axially inwardly of said housing. 10

3. Means providing a swiveling connection between an electric cord and an electrical current supply outlet comprising a cup-shaped receptacle having terminal members extending to the outer surface of said receptacle, a post extending axially in said receptacle and having engagement 15 with one of said terminal members, an insulating cover member having bearing means engaging the extending end of said post providing for rotation of said cover thereabout, said cover having opposed openings for receiving contact members carried by said cord, contact fingers carried by said cover within said receptacle adapted to be engaged by said contact members, means for connecting one of said fingers to said post, means resiliently spacing said cover 20 out of engagement with said receptacle and providing an electrical connection within said receptacle between the other of said contact fingers and the other of said terminal members, and spring means tending to urge said cover axially 25 inwardly of said housing, said spring means being independent of the electrical circuit through said connection.

4. In a swivel connector of the class described, means for extending a circuit connection from a rotatable contact finger to a fixed terminal, comprising a first contact-carrying member having a contact surface having rotatable bearing contact with said terminal, said member having extending contact arms, a second contacting member mounted for conjoint rotation with said first contact member and having extending arm portions resiliently engaging the arms of said first member for rotating said first member about said contact surface upon rotation of said contact finger, said second contact member having a contact surface providing contacting engagement with said finger. 50

5. Means providing a swiveling electrical connection between a flexible electric cord and an electrically operated appliance comprising a pair 55 of terminal conductors connected to said appliance, a terminal housing having a recess therein, a post member extending centrally of said recess and connected at its lower end to one of said conductors, a terminal member connected to the other of said conductors and extending into said recess, said member having a contact surface extending about and insulated from said post, a rotatable insulating member mounted on said 60 post, contact fingers carried thereby, means carried by said insulating member for connecting one of said fingers to said post, resilient rotatable means connected to the other of said fingers and having a contact surface engaging the contact surface of said terminal member, and means for connecting the electrical cord to said contact fingers including an enclosing insulating member 65 extending downwardly over said rotatable member and urging said contact fingers into 70

tight contacting engagement with the conductors carried in said cord.

6. Means providing a swivel connection between a trouble lamp and an electric two-conductor cord comprising a lamp holder, a socket therein, a receptacle carried by said holder, terminal means on said receptacle electrically connected to said socket, a cover for said receptacle having contact members carried thereby, 10 said cover being rotatable coaxially of said receptacle, means carried by said cover for electrically connecting said contact members to said terminal means in all rotative positions of said cover, and an end connection for said cord comprising a pair of terminal lugs having camming plates connected thereto, said camming plates being adapted to connect the conductor of said cord to said contact members and to lock said end connection of said cord for conjoint rotation 15 with said cover.

7. An electrical wall receptacle for providing a plurality of wall outlet connections comprising a wall plate, an insulating housing secured thereto, said housing having a plurality of spaced recesses therein having terminal means including a post extending axially through each of said recesses, said terminal means having a common terminal for said posts, insulating covers for each of said recesses mounted for rotation on said 20 posts, spring means about said post holding said covers out of frictional engagement with said housing driving rotation thereof, contact means carried by each of said covers and disposed within said recesses, and means for maintaining electrical connection between said contact means and said terminal means during rotation of said covers.

8. Swiveling connector means comprising a wall plate, an insulating housing secured thereto and having spaced cylindrical recesses formed therein and aligned with openings in said plate, terminal posts extending centrally through each of said recesses, cover members disposed in said openings and rotatably mounted on said posts, 40 opposed contact fingers carried by each of said covers and rotatable therewith within said recesses, said cover member having openings therethrough providing for access to said contact fingers within said recesses, a common terminal lug for said terminal posts, means for connecting one of said contact fingers in each of said recesses to said posts, terminal means in each of said recesses insulated from said posts and having a common terminal lug, and rotatable resilient contact means carried by each of said covers 45 for connecting the other of said contact fingers

to said terminal means, said contact fingers being electrically connected to the respective terminal lugs in all rotative positions of said covers.

9. In a device of the class described, a cup portion of non-conductive material, a plug portion of non-conductive material having substantially its entire body rotatably mounted in said cup portion, an elongated metallic sleeve mounted in said plug portion, a metallic shaft element operatively secured at one end to said cup portion and having a substantial portion of its length journaled in said sleeve, a means for limiting the longitudinal sliding movement of said plug portion relative to said cup portion in both directions, a metallic collar fixed to the inside bottom of said cup portion arranged concentrically with said shaft element and said plug and cup portions, a metallic ring rotatably mounted around said collar, two spring arms diametrically extending from said ring member, an elongated metallic member having notches in both of its ends for receiving the outer end portions of said spring arms respectively, an electricity conducting member connected to said elongated metallic member, an electricity conducting member leading from 10 said sleeve, an electricity conducting member 15 electrically connected to said shaft element, and an electricity conducting member connected to said collar.

10. In a device of the class described, a cup portion of non-conductive material having a hollow projection arising from its inside bottom, a plug portion of non-conductive material having substantially its entire body rotatably mounted in said cup portion, an elongated metallic sleeve 30 mounted in the center portion of said plug portion, a metallic shaft element secured to said cup portion and extending through said sleeve, a means for limiting the longitudinal sliding movement of said plug portion relative to said cup portion in 35 both directions, a cone shaped metallic collar fixed around the said projection arising from the inside bottom of said cup portion, a metallic ring rotatably mounted around said metallic collar, two spring arms diametrically extending from 40 said ring, an elongated metallic member having notches in both of its ends and receiving the outer end portions of said spring arms respectively, an electricity conducting member connected to said elongated metallic member, an electricity 45 conducting member leading from said sleeve, an electricity conducting member electrically connected to said shaft element, and an electricity conducting member connected to said collar.

55

ALBERT E. CALDWELL.

CERTIFICATE OF CORRECTION.

Patent No. 2,134,355.

October 25, 1938.

ALBERT E. CALDWELL.

It is hereby certified that error appears in the printed specification of the above numbered patent requiring correction as follows: Page 7, first column, line 32, claim 7, for the word "driving" read during; and that the said Letters Patent should be read with this correction therein that the same may conform to the record of the case in the Patent Office.

Signed and sealed this 6th day of December, A. D. 1938.

Henry Van Arsdale

(Seal)

Acting Commissioner of Patents.
